UNITED STATES PATENT OFFICE.

BENNO F. JANCKE, OF BROOKLYN, NEW YORK, ASSIGNOR, BY MESNE ASSIGNMENTS, TO HALLIWELL-SHELTON ELECTRIC CORPORATION, OF NEW YORK, N. Y., A CORPORATION OF NEW YORK.

AIR-PURIFYING DEVICE.

Application filed January 31, 1923. Serial No. 616,092.

This invention relates to air purifying devices producing ozone, and provides improvements therein.

The present invention provides a simple, inexpensive, and efficient device for use in chambers such as sick-rooms, crowded rooms, salons, ice boxes, refrigerators, telephone and talking machine booths, or the like, for purifying the air therein by the generation of ozone and also preferably by lading the air with ozonized medicated vapor or with an odorament, or the like, the volatilization or gasification of which is assisted by the heat produced by the diffused high tension discharge of the ozone generator.

It further provides an apparatus having means for producing a high-frequency current in the discharge circuit thereby making the apparatus safe for use where persons are apt to come into contact with the apparatus.

An embodiment of the invention is illustrated in the accompanying drawings, in which—

Figure 1 is a perspective view of the device.

Fig. 2 is a vertical sectional view through the apparatus.

Fig. 3 is a top plan view, and

Fig. 4 is a diagrammatic view showing the electrical ensemble.

Referring to said drawings, numeral 10 designates an electrode and 12 another electrode or a suitable capacity, between which electrode and capacity an electrical discharge is adapted to be produced for acting on the air to convert the oxygen thereof to ozone. The electrode 10 is preferably in the form of a cup or receptacle, adapted to contain a medicament (liquid or solid) or odorament, or the like, vaporization of which will be assisted by the heat produced by the electrical discharge at the electrode. In practice the electrode 10 is conveniently in the form of a metallic tube 15 within a dielectric such as glass 17, in the form of a cup or vase, and having a contracted end 19 adapted to fit in a socket 21 in a pedestal 23, which later, as here shown, may be attached to a casing 25 for certain of the electrical parts, and may project through an opening 27 in a top or cover 29 of said casing. On the contracted end 19 of said cup 17 there is

a metal thimble 31, which is connected to the tube 15 on the inside of the cup 17 by a wire 33 passing through a seal in the glass cup 19. A similar metal thimble 35 is placed in the socket 21, in which the end 19 of the cup with its thimble 31 thereon, constituting a plug, is adapted to make contact, the parts just described constituting a slip-joint plug and socket electrical connection between the cup 17 and pedestal 23.

40 designates the parts for generating the high-frequency high-tension current employed, these parts being conveniently housed in the casing 25, and the current for energizing is preferably taken from the lighting circuit through the terminals 42, 43, Fig. 4. As the apparatus is relatively small and self-contained, and may be connected to any of the outlets of a household lighting circuit, it is portable and readily adapted for household use.

The generating apparatus comprises a transformer or resonator 45 having a primary 46 and a secondary 47, which latter is connected to the electrode 10, as indicated at 48, being immediately connected to the thimble 35 in the socket 21. The primary 46 is connected to one of the terminals 43 by way of conductors 50, 51, and to the other terminal 42 by way of conductor 55, inductance 56, conductors 57, 58, interrupter 59, contact 60, and conductor 61. Shunted across the leads to the primary, and in resonance therewith, is a condenser 65, connected to conductors 51 and 57 as indicated at 66, 67.

The secondary 47 is grounded conveniently on one of the primary leads as indicated at 70.

When a connection is established through the terminals 42, 43 with a lighting circuit, current flows from terminal 42 through conductor 55, inductance 56, conductors 57, 58, armature or interrupter 59, contact 60, conductor 61, and primary 46, and conductors 50 and 51 to terminal 43. When the armature or interrupter 59 is drawn away by the electromagnetic effect of the coil 56, a short spark is produced between the armature 59 and contact 60, thereby setting up a high-frequency oscillation from the condenser 65. These high-frequency oscillations passing through the primary 46 produce a high elec-

tromotive force in the secondary 47, which is sufficient to overcome the dielectric effect of the glass 17, causing a discharge between the electrode 10 and capacity 12. The capacity 12 is conveniently in the form of a metal tube 75 surrounding the electrode 10, and connected to ground or a body of large capacity (such as the dynamo and lighting circuit) by being connected to one of the primary leads, as indicated at 70, through a conductor 77 and the metallic parts of a post 78 from which the capacity 12 is supported. In order to increase spark area, the tube 75 is preferably provided with many points, 15 or spiculated, thereby producing a great number of sparks, and a high rate of ozone generation. The tube 75 is moreover preferably divided into two or more segmental parts, so as to be readily put in place around 20 the glass 17, and removed, and is held together by a clamp 80 having an arm 81 fitting in a metal knob 82 in the post 78.

The ozone will purify the air, and increase the activity of the oxygen thereof, and the 25 medicament or odorament, which will be volatilized by the heat of the electric discharge, may also purify the air or medicate or sterilize it.

If a part of the body is brought into contact with or close to the electrode 10, the discharge to the body will not be injurious or 30 highly disagreeable, owing to the high frequency of the current employed, which is over 10,000 oscillations per second, and may 35 be, for example, about 60,000 oscillations per second.

The inventive ideas may receive other embodiments than that herein specifically illustrated and described.

40 4. What I claim is:—

1. An air purifying device, comprising electrodes adapted for the production of ozone, one of said electrodes comprising a liquid receptacle adapted to be heated by the 45 discharge from said electrodes, whereby liquid contents thereof may be volatilized.

2. An air purifying device, comprising electrodes adapted for the production of ozone, said electrodes being substantially 50 extensive throughout their areas, one of said electrodes comprising a liquid receptacle adapted to be heated by the discharge from said electrodes, whereby liquid contents thereof may be volatilized.

55 3. An air purifying device, comprising electrodes adapted for the production of ozone, said electrodes being substantially co-extensive throughout their areas, one of said electrodes comprising a liquid receptacle 60 adapted to be heated by the discharge from said electrodes, whereby liquid contents thereof may be volatilized, a rigid dielectric separating said electrodes and the other of

said electrodes being in the form of a split cylinder surrounding said dielectric. 65

4. An air purifying device, comprising electrodes adapted for the production of ozone, said electrodes being substantially co-extensive throughout their areas, one of said electrodes comprising a liquid receptacle 70 adapted to be heated by the discharge from said electrodes, whereby liquid contents thereof may be volatilized, a rigid dielectric separating said electrodes and the other of said electrodes being in the form of a split cylinder surrounding said dielectric, and a clamp for holding said cylinder parts together on said dielectric. 75

5. An air purifying device, comprising electrodes adapted for the production of ozone, said electrodes being substantially co-extensive throughout their areas, one of said electrodes comprising a liquid receptacle 80 adapted to be heated by the discharge from said electrodes, whereby liquid contents thereof may be volatilized, a rigid dielectric separating said electrodes and the other of said electrodes being in the form of a split cylinder surrounding said dielectric, a clamp 85 for holding said cylinder parts together on said dielectric, and a ground attachment, said clamp being fastened on said ground attachment. 90

6. An air purifying device for chamber use, comprising an exposed electrode adapted 95 for the production of ozone, and means for producing high frequency high potential differences at said electrode, whereby a high potential heating and discharge current without dangerous effect on the human system 100 may be produced at said electrode. 100

7. An air purifying device for chamber use, comprising an exposed electrode adapted for the production of ozone, means for supplying said device with current from a lighting circuit, and means for transforming said current to one of a high voltage and high frequency at said electrode, whereby a high potential heating and discharge current without dangerous effect on the human system 105 may be produced at said electrode. 110

8. An air purifying device adapted for the production of ozone, comprising a pair of substantially cylindrical spaced electrodes, the surface of one of said electrodes being 115 multi-pointed.

9. An air purifying device adapted for the production of ozone, comprising a pair of substantially cylindrical spaced electrodes, one of said electrodes being in the form of a liquid receptacle and the other of said electrodes having a spinose surface. 120

In witness whereof, I have hereunto signed my name.

BENNO F. JANCKE.
